FUNNEL FOR A SANITARY SPECIMEN COLLECTOR

Michael H. Sherin, Fontana, Wis., assignor to Sage
Products Inc., Elk Grove, Ill.

Continuation-in-part of design application Ser. No.
133,484, Apr. 12, 1971. This application Mar. 16,
1972, Ser. No. 222,816

Term of patent 14 years

Int. Cl. D24

U.S. CL. D83—1 U

Fig. 7.

Fig. 8.

Fig. 9.

Fig. 10.

Fig. 11.

Fig. 12.

FIG. 1 is a top perspective view of a funnel for a sanitary specimen collector showing my new design;

FIG. 2 is a bottom perspective view thereof;

FIG. 3 is a side elevation thereof;

FIG. 4 is a top perspective view of a second modified embodiment of the funnel illustrated in FIG. 1;

FIG. 5 is a bottom perspective view thereof;

FIG. 6 is a side elevation thereof;

FIG. 7 is a front perspective view of a third modified embodiment of the funnel illustrated in FIG. 1;

FIG. 8 is a bottom perspective view thereof;

FIG. 9 is a side elevation thereof;

FIG. 10 is a top perspective view of a fourth modified embodiment of the funnel illustrated in FIG. 1;

FIG. 11 is a bottom perspective view thereof; and

FIG. 12 is a side elevation thereof.

The broken lines are shown for illustrative purposes only.

This is a continuation-in-part of design application Ser. No. D. 133,484, filed Apr. 12, 1971, and now abandoned.

I claim:

The ornamental design for a funnel for a sanitary specimen collector, as shown and described.
